Inventor:

Joseph Lelyveld

by night or Brown County May

1925.

UNITED STATES PATENT OFFICE.

JOSEPH LELYVELD, OF ROCKLAND, MASSACHUSETTS.

ARCH SUPPORTER.

Application filed September 16, 1924. Serial No. 737,962.

To all whom it may concern:

Be it known that I, JOSEPH LELYVELD, a citizen of the United States, residing at Rockland, in the county of Plymouth and State of Massachusetts, have invented new and useful Improvements in Arch-Supporters, of which the following is a specification.

This invention is embodied in an arch-supporting plate of resilient sheet metal, such as tempered steel, stellite, etc., adapted to be interposed between the outer and inner soles of a shoe, and to so support the inner sole as to cause the latter to act as hereinafter described, in supporting and maintaining various portions of the bones of the human foot.

Of the accompanying drawings forming a part of this specification,—

Figure 1 is a plan view, showing the bones of a normal human foot, and showing by dotted lines an arch supporter embodying the invention, in the position relative to the foot which it occupies when in use.

Figure 2 is a plan view showing the supporter alone.

Figure 3 is a section on line 3—3 of Figure 2.

Figure 4 is a section on line 4—4 of Figure 2.

Figure 5 is a section on line 5—5 of Figure 2, and shows portions of a shoe by dotted lines.

The same reference characters indicate the same parts in all of the figures.

An arch-supporter embodying the invention is a one piece resilient sheet metal plate, preferably of tempered steel or stellite, having sufficient resilience to enable parts of the plate to yieldingly support portions of an inner sole 12. The plate is adapted to be interposed between the inner sole and the outer sole 13, and is preferably provided with means, such as upstanding spurs 14, for engaging the inner sole and holding the plate in a predetermined position. The plate has a relatively wide anterior end portion 15, a narrower posterior end portion 16, a relatively long curved inner longitudinal edge portion or span 17, formed to extend from the oscalcis to the base of the first metatarsal, and a shorter curved outer longitudinal edge portion 18, formed to extend forward from the oscalcis to the base of the fifth metatarsal.

The plate is cut away to provide apertures 19 and 20, between the portions 17 and 18, permitting independent flexures of said portions. The inner edge portion 17 provides a yielding support for the inner weight-carrying points of the foot. The outer edge portion 18 provides a yielding support for the outer weight-carrying points.

The plate has a transverse arched portion or cross span 21, between the apertures 19 and 20, adapted to maintain the transverse arch y, y , which extends between the cuboid and the internal cuneiform, and to permit independent flexures of the portions 17 and 18.

The anterior end portion of the plate includes a concavo-convex dome 22, preferably extended forward, and adapted to maintain the dome-like arching of the anterior metatarsal arch x, x , composed of the second, third and fourth metatarsals, the first and fifth metatarsals being the bridging or base points of said arch, and the dome 22 being between said points as shown by Figure 1.

It will be understood that the inner sole 12 is sufficiently flexible to enable it to conform to the upper surfaces of the plate, so that the inner sole forms a support for the various portions or bones of the foot above mentioned.

The curvature of the edge portions 17 and 18 is such that said portions are normally spaced throughout the major portion of their length from the outer sole, and are adapted to yield between their ends to downward pressure, and to permit a limited yielding of the arched cross span 21 and the dome 22.

Owing to the one-piece construction of the supporting plate, the parts being integral with each other, the plate is adapted to be expeditiously formed by suitable dies, with its parts in a fixed and invariable relation to each other, without an assembling operation, following the forming operation, the plate being insertable as a unit between an outer and an inner sole. There are no overlapping parts, so that all portions of the plate are of uniform thickness.

The plate may be cut out from sheet material by a single operation, which includes the molding of the portions 21 and 22, and the cutting away of material to form the apertures 19 and 20.

I claim:

1. A one-piece arch-supporting plate of resilient sheet material, adapted to be interposed as a unit between an outer and an inner sole, and including an inner longitudinal curved edge portion formed to extend from the oscalcis to the base of the first metatarsal, an outer longitudinal curved edge portion formed to extend from the oscalcis to the base of the fifth metatarsal, and anterior and posterior end portions integral with and connecting said edge portions, the plate being cut away between the edge portions and between the end portions to permit independent flexure of the edge portions.

2. A one-piece arch-supporting plate of resilient sheet material, adapted to be interposed as a unit between an outer and an inner sole, and including an inner longitudinal curved edge portion formed to extend from the oscalcis to the base of the first metatarsal, an outer longitudinal curved edge portion formed to extend from the oscalcis to the base of the fifth metatarsal, anterior and posterior end portions integral with and connecting said edge portions, the plate being cut away between the edge portions and between the end portions to permit independent flexure of the edge portions, and a transverse arched portion integral with and connecting the edge portions between cut away portions of the plate and adapted to permit said independent flexure and to maintain the transverse arch between the cuboid and the internal cuneiform.

3. A one-piece arch-supporting plate of resilient sheet material, adapted to be interposed as a unit between an outer and an inner sole, and including an inner longitudinal curved edge portion formed to extend from the oscalcis to the base of the first metatarsal, an outer longitudinal curved edge portion formed to extend from the oscalcis to the base of the fifth metatarsal, and anterior and posterior end portions integral with and connecting said edge portions, the plate being cut away between the edge portions and between the end portions to permit independent flexure of the edge portions, the anterior end portion being dome-shaped and adapted to maintain the dome-like form of the anterior metatarsal arch.

4. An arch-supporting plate of resilient sheet metal, adapted to be interposed between an outer and an inner sole, and to extend forward from the oscalcis nearly to the anterior metatarsal arch, said plate having a relatively wide forward end portion, a narrower rear end portion, an inner longitudinal curved edge portion formed to extend from the oscalcis to the base of the first metatarsal, an outer longitudinal curved edge portion formed to extend from the oscalcis to the base of the fifth metatarsal, the plate being apertured between said end portions to permit independent flexure of said edge portions, a transverse arched portion between its ends adapted to maintain the transverse arch between the cuboid and the internal cuneiform, and a dome-shaped portion at its forward end, adapted to maintain the dome-like form of said anterior transverse arch.

In testimony whereof I have affixed my signature.

JOSEPH LELYVELD.

inner sole, and including an inner longitudinal curved edge portion formed to extend from the oscalcis to the base of the first metatarsal, an outer longitudinal curved edge portion formed to extend from the oscalcis to the base of the fifth metatarsal, and anterior and posterior end portions integral with and connecting said edge portions, the plate being cut away between the edge portions and between the end portions to permit independent flexure of the edge portions, the anterior end portion being dome-shaped and adapted to maintain the dome-like form of the anterior metatarsal arch. 40 45 50

4. An arch-supporting plate of resilient sheet metal, adapted to be interposed between an outer and an inner sole, and to extend forward from the oscalcis nearly to the anterior metatarsal arch, said plate having a relatively wide forward end portion, a narrower rear end portion, an inner longitudinal curved edge portion formed to extend from the oscalcis to the base of the first metatarsal, an outer longitudinal curved edge portion formed to extend from the oscalcis to the base of the fifth metatarsal, the plate being apertured between said end portions to permit independent flexure of said edge portions, a transverse arched portion between its ends adapted to maintain the transverse arch between the cuboid and the internal cuneiform, and a dome-shaped portion at its forward end, adapted to maintain the dome-like form of said anterior transverse arch. 70 75 80 85

In testimony whereof I have affixed my signature.
